UNITED STATES PATENT OFFICE.

JOSEPH L. CATO, OF ELMHURST, NEW YORK, ASSIGNOR TO L-W-F ENGINEERING COMPANY INC., OF COLLEGE POINT, LONG ISLAND, NEW YORK, A CORPORATION OF MICHIGAN.

FUSELAGE CONSTRUCTION FOR AEROPLANES.

Application filed November 7, 1919. Serial No. 336,288.

To all whom it may concern:

Be it known that I, JOSEPH L. CATO, a citizen of the United States, residing at Elmhurst, in the county of Queens and State of New York, have invented a certain new and useful Improvement in Fuselage Constructions for Aeroplanes, of which the following is a specification.

My invention relates particularly to a construction adapted to be used for fuselages and has reference especially to the strengthening means carried thereby.

The object of my invention is to provide a fuselage construction in which transverse strengthening plates of an advantageous character are used.

Another advantage is to provide such strengthening plates which are capable of being readily secured in place in the fuselage without necessitating a large expenditure of labor in the installation of the same.

Again, another object of my invention is to provide strengthening plates which are provided with straight sides arranged to be secured to the curved interior of the fuselage.

Further objects of my invention will appear from the detailed description thereof contained hereinafter.

While my invention is capable of embodiment in many different forms, for the purpose of illustration, I have shown only one way of carrying out the same in the accompanying drawings, in which—

Fig. 1 is a transverse section of a fuselage made in accordance with my invention and showing one of the transverse strengthening plates in elevation, and

Fig. 2 is a fragmental side elevation of one of the strengthening plates.

In the drawings, I have shown in cross section a monocoque fuselage 1 made of a plurality of alternating laminations of wood and woven fabric secured together with glue. In the interior of the fuselage there are provided any number of transverse strengthening plates 2. Each of these plates 2 is made up of a plurality of layers of wood 3, 4 and 5 with the grain of layers of wood crossing one another and the different layers being secured together with glue. As shown in Fig. 1 the strengthening plate 2 has a number of triangular openings 3" having edges 3' from which portions of wood which

have been removed to lessen the weight without materially affecting the strength of the plate. Furthermore, said plate is provided with straight sides in order to facilitate its manufacture and in order to enable it to be readily fitted to different fuselages. The plate 2 at its upper and lower edges fits against upper and lower bracing bars 6 and 7 which are of tubular character and extend entirely through the fuselage for the purpose of receiving at their ends in eye brackets 8, 9, 10 and 11, the ends of the struts carried by the aeroplane. The plate 2 is secured to the bracing bars 6 and 7 by means of metal straps 12 having tongues 13 and 14 which are folded over and around the bracing bars 6 and 7 and are secured to the plate 2 on opposite sides thereof by means of rivets 15. Furthermore, on opposite sides of the plate 2, and at each corner thereof, there are provided angle brackets 16, one wing of 75 each of which fits over the top of the strap and the other wing of which fits against the interior surface of the fuselage, rivets 17 being provided to secure said wings in place.

The operation of my invention will be clearly understood from the foregoing description of the construction. A fuselage to be equipped with my invention has first introduced into the same the desired number of bracing plates 2, each of the same being 85 provided at the four corners thereof with straps 12. Thereafter the bracing bars 6 and 7 are passed through the body of the fuselage and the straps 12. The plate is then firmly secured in place by introducing 90 the angle brackets 16 and securing them both to the fuselage and the plates. It will also be noted, with this method of applying transverse strengthening plates where it is not necessary to fit the edges of the plate 95 against the curved interior surface of the fuselage, that the bracing plates 2 may be of an interchangeable size and shape. That is to say, they may be inserted at any one of a number of different points along the fuselage.

While I have described my invention above in detail, I wish it to be understood that many changes may be made therein without departing from the spirit thereof.

I claim:

1. In combination, a fuselage, a transverse strengthening plate therein, means for at-

taching the plate to the fuselage without the necessity of having the shape of the plate conform to the shape of the fuselage comprising a transverse bracing bar and means 5 for securing the plate to the bar.

2. In combination, a fuselage, a transverse strengthening plate therein, means for attaching the plate to the fuselage without the necessity of having the shape of the plate 10 conform to the shape of the fuselage comprising a transverse bracing bar and means for securing the plate to the bar including a strap passing around the bar and secured to the plate.

15 3. In combination, a fuselage, a transverse strengthening plate therein, means for attaching the plate to the fuselage without the necessity of having the shape of the plate conform to the shape of the fuselage comprising a transverse bracing bar and means 20 for securing the plate to the bar including a strap passing around the bar and secured to the plate at the corner of the plate.

4. In combination, a fuselage, a transverse strengthening plate therein, means for attaching the plate to the fuselage without the necessity of having the shape of the plate 25 conform to the shape of the fuselage comprising an angle bracket, a transverse bracing bar and means for securing the plate to the bar.

30 5. In combination, a fuselage, a transverse strengthening plate therein, means for attaching the plate to the fuselage without the necessity of having the shape of the plate 35 conform to the shape of the fuselage comprising an angle bracket, a transverse bracing bar and means for securing the plate to the bar including a strap passing around the 40 bar and secured to the plate.

6. In combination, a fuselage, a transverse strengthening plate therein, means for attaching the plate to the fuselage without the necessity of having the shape of the plate 45 conform to the shape of the fuselage comprising an angle bracket, a transverse bracing bar and means for securing the plate to the bar including a strap passing around the bar and secured to the plate at the corner of the plate.

50 7. In combination, a fuselage, a rectangular transverse strengthening plate therein, means for attaching the plate to the fuselage without the necessity of having the shape 55 of the plate conform to the shape of the fuselage comprising an upper and a lower

transverse bracing bar and means for securing the plate to each of said bars.

8. In combination, a fuselage, a rectangular transverse strengthening plate therein, 60 means for attaching the plate to the fuselage without the necessity of having the shape of the plate conform to the shape of the fuselage comprising an upper and a lower transverse bracing bar and means for 65 securing the plate to each of said bars including a strap passing around the bars and secured to the plate.

9. In combination, a fuselage, a rectangular transverse strengthening plate therein, 70 means for attaching the plate to the fuselage without the necessity of having the shape of the plate conform to the shape of the fuselage comprising an upper and a lower transverse bracing bar and means for securing 75 the plate to each of said bars including a strap passing around the bars and secured to the plate at the corner of the plate.

10. In combination, a fuselage, a rectangular transverse strengthening plate therein, 80 means for attaching the plate to the fuselage without the necessity of having the shape of the plate conform to the shape of the fuselage comprising an angle bracket, an upper and a lower transverse bracing bar 85 and means for securing the plate to each of said bars.

11. In combination, a fuselage, a rectangular transverse strengthening plate therein, 90 means for attaching the plate to the fuselage without the necessity of having the shape of the plate conform to the shape of the fuselage comprising an angle bracket, an upper and a lower transverse bracing bar 95 and means for securing the plate to each of said bars including a strap passing around the bars and secured to the plate.

12. In combination, a fuselage, a rectangular transverse strengthening plate therein, 100 means for attaching the plate to the fuselage without the necessity of having the shape of the plate conform to the shape of the fuselage comprising an angle bracket, an upper and a lower transverse bracing bar 105 and means for securing the plate to each of said bars including a strap passing around the bars and secured to the plate at the corner of the plate.

In testimony that I claim the foregoing, I have hereto set my hand this 11th day of October, 1919.

JOSEPH L. CATO.
